PHOTOMETER LAMP CIRCUITS PROVIDING
A STANDARD VOLTAGE

Robert William Gainer Hunt, Harrow, Wealdstone, England, assignor to Eastman Kodak Company, Rochester, N. Y., a corporation of New Jersey

Application February 12, 1947, Serial No. 728,069
In Great Britain November 15, 1946

1 Claim. (Cl. 88—23)

1

The present invention relates to the obtaining of a predetermined standard brightness of an electric lamp and more particularly to an arrangement whereby an electric incandescent lamp may be made to provide a standard brightness without the aid of electric measuring instruments. The invention finds its primary use in photometers with which illumination of unknown brightness is compared with a standard brightness in any well known manner.

An object of the present invention is the provision of a circuit arrangement making it possible to cause a predetermined current to flow through, or a predetermined voltage applied to, a lamp without employing a special measuring instrument.

Another object of the invention is the provision of a method for bringing a lamp to a standard brightness which does not require a voltmeter.

Other objects and advantages of the invention will appear from the following description when read in connection with the accompanying drawing in which:

Fig. 1 is a circuit diagram of a simple arrangement embodying the invention; and

Fig. 2 is a graph illustrating the principle underlying the operation of the invention.

In many photometers an object whose brightness is to be measured is compared visually with a standard brightness, such as an electric lamp, contained in the photometer by altering in any desired manner the apparent brightness of either the object or the lamp until the two appear equally bright, the magnitude of the alteration being a measure of the brightness of the object. Other photometers and other apparatus require a light source of standard brightness and the arrangement and method described below are directed to securing a standard brightness regardless of the particular use to be made thereof.

In order for a lamp to provide a truly standard brightness, it must always operate at the same voltage. In the absence of a constant voltage source or a voltmeter, it is difficult to insure this same voltage and many devices have been developed for this purpose. Among such devices are those in which a known resistance is removed from a lamp circuit to boost the energization of the lamp a certain amount above its glow level, or resistances having different temperature coefficients are alternately inserted in a lamp circuit to determine when the current reaches a predetermined value, and those having built-in optical pyrometers for ascertaining when

2

the lamp filament reaches a predetermined color temperature.

In accordance with the present invention two similar lamps are so arranged with respect to a photometer head that a brightness match is obtained only at a unique level. This may be accomplished as shown in Fig. 1 by connecting two lamps C and D in parallel across a battery 40 and its controlling resistance 11 and connecting 10 in series with the lamp C a fixed resistance 12 to lower the voltage V_C on the lamp C below the voltage V_D on the lamp D so that the lamp C will be less bright than lamp D. Now if the resistance 11 is adjusted to give lamp D its desired 15 standard brightness and then a photometer head 13 is placed between the two lamps C and D in such a way that the portions of the fields illuminated by the two lamps are equally bright, as by inserting a neutral density filter in front of the 20 lamp D or by placing the head 13 nearer to the lamp C than to the lamp D, any future adjustment of the resistance 11 to match the two fields 25 on the head 13 will automatically insure that the lamp D has the same brightness as was previously selected as standard.

The lamp C will, of course, in each case be brought to its former brightness and may comprise a standard different from that furnished by the lamp D.

30 The reason why the two lamps C and D will always operate at standard voltages whenever a match is obtained in the photometer head 13 will be clear from the graph of Fig. 2 in which the brightness B_D of that part of the photometer head field illuminated by the lamp D is plotted 35 against the voltage V_D across the lamp D to obtain curve D, and the brightness B_C of that part of the photometer head field illuminated by the lamp C is also plotted against the voltage V_D to obtain the curve C. Since the two lamps C and 40 D are similar the two curves would be similar in shape to curve D if both were plotted against the voltage V_C and V_D across the respective lamps C and D. But since the curve C is that of B_C plotted against V_D (the voltage across the lamp C and the resistance 12) the shape of the curve C will be similar to that of curve D but will be stretched out along the voltage axis. Furthermore, since the head 13 is effectively or actually 45 nearer to the lamp C than to the lamp D, the curve C will be magnified along the brightness axis. Thus, the curve C may be approximately described as being a magnified replica of the curved tail of the curve D, the magnification 50

along the brightness axis being greater than that along the voltage axis.

Under the circumstances described above it is clear that the curves C and D intersect at one point only and hence at one voltage V_s . At this standard voltage V_s , the two parts of the photometer head field are of equal brightness, i. e., $B_c=B_d$. Now any time the resistance 11 is adjusted to obtain a match in the photometer head 13 it is known that the voltage V_d across the lamp D has been adjusted to the standard value V_s and accordingly the brightnesses of the lamps C and D are standardized.

Inasmuch as the lamps C and D receive different voltages they will radiate at different colors. Such color difference may be compensated by a filter 14 incorporated in the photometer head 13 or interposed between the head 13 and one of the lamps so that the two portions of the photometer field automatically match one another in color when the brightness match is obtained. Using ordinary flash lamp bulbs and a dry battery it has been found to be quite easy to standardize the brightness of the brighter bulb to within five per cent.

In practicing the invention the operator adjusts the resistance 11 until a match is obtained on the photometer head 13 at which time he knows that the two lamps C and D are at their predetermined brightnesses. The operator then compares the brightness of an object under investigation with one of the lamps. This comparison of the unknown light with one of the lamps may be made in any well known manner, one suitable arrangement being shown in Fig. 1 as comprising a comparison screen 15 upon the upper half of which the unknown light is permitted to fall. Light from the standard lamp, here shown as lamp D, is directed onto the lower half of the screen 15 by a reflector 16 through a light-

modifying device which may be a density wedge 17 arranged in annular form for rotation with a shaft 18. The angular position of the wedge 17 when a match is obtained on the screen 15 is of course a measure of the brightness of the unknown light.

It will be understood that the drawing is diagrammatic and that only those parts are shown which are necessary to an understanding of the invention. Other arrangements may be employed in practicing the invention without departing from the scope of the appended claim.

I claim:

15 In a photometer, a photometer head, a photometric lamp for providing light of known brightness, optical means for directing light of unknown brightness and the light of known brightness into adjacent relationship for comparison purposes, means for adjusting the lamp to a predetermined brightness comprising means for varying the voltage applied to the lamp, a second lamp and a resistance connected in series across the terminals of the photometric lamp, whereby a predetermined brightness difference between 20 the two lamps exists for a unique voltage, and photometric means for ascertaining when a desired brightness difference exists between the two lamps.
